CATCHING DEVICE FOR WELL TUBING

Filed Aug. 19, 1927

FIG. 1.

FIG. 3.

FIG. 4.

FIG. 2.

Inventor

STEPHEN V. DILLON,

By George A. Prevost

Attorney

UNITED STATES PATENT OFFICE.

STEPHEN V. DILLON, OF TULSA, OKLAHOMA.

CATCHING DEVICE FOR WELL TUBING.

Application filed January 19, 1927. Serial No. 162,044.

This invention relates to improvements in tubing catchers for oil wells and the like, and more particularly to tubing catchers of the type employing a wedge block to expand gripping slips into engagement with a well casing.

The primary object of the invention is to provide a tubing catcher capable of automatically catching and supporting a tubing string in case there is breakage of the string above the catcher, and also adapted to be set by the operator at any desired point in the well.

Another object of the invention is to furnish a tubing catcher which may be lowered with the tubing and anchored at a desired elevation, such catcher being constructed to permit the tubing to reciprocate therein during pumping or the like.

A still further object is to provide automatic means for setting the catcher, adapted to be actuated by combined gas pressure and friction forces.

Another object is to furnish a tubing catcher having a slip assembly including a pivoted vane or vanes adapted in case of a breakage of the string, to increase its sustaining area horizontally under the influence of gas pressure in the well, and to scrape along the inner surface of the well casing for actuating the slips which anchor the catcher in the well.

With the foregoing objects outlined and with other objects in view which will appear as the description proceeds, the invention consists of the novel features hereinafter described in detail, illustrated in the accompanying drawing and more particularly pointed out in the appended claims.

Referring to the drawings,

Fig. 1 is a side elevation of one form of my invention shown in the position which it occupies while descending a well with the tubing.

Fig. 2 is a perspective view of the vane forming a detail of the structure shown in Fig. 1.

Fig. 3 is a view similar to Fig. 1, of the lower portion of my device provided with a different form of vane or retarding means.

Fig. 4 is a perspective view of the vane used with the structure shown in Fig. 3.

In the drawing, 1 designates a string of tubing while descending in a well casing 2.

3 A collar 3 is fixed on the tubing and supports a wedge sleeve 4 which is slidably

mounted on the tubing. This wedge sleeve forms a weight member and it is tapered downwardly as illustrated in the drawing. Fingers 5 project from the wedge sleeve and function as guides for the stems 6 of slips 7. Only one slip and stem is shown, but it is to be understood that a similar slip and stem is arranged at the rear side of the wedge block.

Each stem is pivotally connected at its lower end to a pivot pin 8 carried by ears 9 projecting from a guide sleeve 10, which is also slidably mounted on the tubing between the collar 3 and a pin 11; the latter projecting radially from the tubing. The sleeve 10 rests on the pin 11 while the tubing catcher is being lowered with the string. A vane or gas pressure actuated device 12 is pivotally mounted on the guide sleeve 10.

The member 12 consists of a ring 13 having a circular edge 14 and an elliptical opening or slot 15. Ears 16 project from the ring 13 and are provided with elongated slots 17 which engage pins 18 projecting from the sleeve 10. While the tubing catcher is descending with the tubing, the ring 13 will assume the position shown in Fig. 1, due to the fact that the ears 16 are slightly offset relatively to one diameter of the ring 13. Consequently, air or gas in the well casing will pass between the edge of the ring 13, and the casing, while the catcher is slowly descending with the tubing.

If, however, the tubing should suddenly drop, the air or other fluid pressure in the casing will tend to move the ring 13 into a horizontal position, and the ring will then retard the downward movement of the slip assembly. When the ring 13 moves into a horizontal position, its edge 14 will frictionally engage the casing and this friction action combined with the fluid pressure below the ring 13, will quickly retard the downward movement of the slip assembly to such an extent that the wedge sleeve 4 will move downwardly relatively to the sleeve 10 and cause the slips 7 to expand and grip the casing.

My improved tubing catcher also includes means to permit the catcher to be set by the operator at any desired elevation in the well. This means consists of a sleeve 19 in which the tubing may turn or slide. The sleeve is provided with bowed friction springs 20 which always bear against the

casing under sufficient pressure to hold the sleeve 19 stationary at any desired point.

The sleeve 19 is provided with a vertical slot 21 merging at its upper end into a horizontal notch 22, in which the pin 11 rests while the catcher is lowering in the well.

When the tubing is descending and the operator desires to set the catcher at a certain elevation, he turns the tubing from

10 the top of the well so as to move the pin 11 into the slot 21. While this movement is taking place, the springs 20 will prevent the sleeve 19 from turning with the tubing.

When the pin 11 reaches the slot 21, the 15 tubing is lowered, and this permits the tubular guide 10 to rest on the sleeve 19 while the wedge block 4 descends with the tubing, to expand the slips 7 and latch the device in position.

20 When it is desired to release the catcher, the tubing is raised until the collar 3 raises the wedge block 4. This will release the slips, and when the pin 11 reaches the lower end of the tubular guide 10, it will lift the latter with the tubing. The sleeve 19 will then be carried along by a lower collar 23.

While the device is being thus raised, if a breakage occurs in the tubing string, the springs 20 will immediately halt the downward movement of the sleeve 19, and the pin 11 will again descend in the slot 21. The tubular guide 10 will strike the upper end of the sleeve 19, and the slip assembly will thus be halted while the wedge block 25 4 continues to descend and again expands the slip 7 into locking position.

The device shown in Figs. 3 and 4, differs from the embodiment in Figs. 1 and 2, only in the employment of a different type of 40 vane or pressure actuated ring. The ring 12^a, in this instance, is formed of an inverted cup provided by two sections 24 having elongated slots 25 through which pins 26 extend. These pins project from the tubular 45 guide 10^a. The edge 27 of the ring is so shaped as to assume a substantially circular form when the sections are in the dotted line position in Fig. 3. The top 28 of the ring is provided with an elliptical slot 29 to receive the tubular guide 10^a, and when the sections move to the dotted line 50 position shown in Fig. 3, the slot 29 will assume a substantially circular form, so that its edge will engage the periphery of the tubular guide 10^a.

The vane 12^a in this form of the invention will achieve the same result as the vane 12 in Figs. 1 and 2, but will, of course, operate a little differently. The vane 12^a tends to 60 form a sort of parachute due to fluid pressure beneath the same when the catcher descends at a relatively fast rate of speed.

The vanes 12 and 12^a may be made of metal, rubber, fibre or any suitable material 65 adapted for this purpose. If the ring 12^a

is made of rubber, or some other suitable yielding material, it may be made in a single piece instead of in sections, but it will function always in the same general manner as that indicated above.

I am aware that various changes may be made in the details disclosed without departing from the spirit of the invention as expressed in the claims.

What I claim and desire to secure by Letters Patent is:

1. The combination with a well having tubing arranged therein, of a tubing catcher mounted on the tubing and including a wedge block, a slip assembly and means for retarding the downward movement of the slip assembly when the latter descends in the well beyond a predetermined speed, said retarding means normally assuming a position in which it is out of contact with the wall of the well and functioning under the influence of fluid pressure, and being partially retarded by friction exerted by contact with the wall of the well upon an abrupt drop of the tube.

2. The combination with a well having tubing arranged therein, of a tubing catcher including a wedge block, a slip assembly and retarding means for the latter, said retarding means normally assuming a position in which it is out of contact with the wall of the well and including an element operated by fluid pressure to retard the downward movement of the slip assembly, and adapted to engage the wall of the well to set up frictional resistance tending to retard the descent of the slip assembly.

3. The combination with a well having tubing arranged therein, of a tubing catcher mounted on the tubing and comprising a wedge block, a slip assembly and retarding means for the latter, said wedge block being adapted to expand the slips of the slip assembly into gripping engagement with the wall of the well, and said retarding means including an element normally lying out of contact with the wall of the well and operating under fluid pressure in the well when the slip assembly descends too rapidly, said retarding means at such time, engaging the wall of the well to exert frictional resistance to the descent of the slip assembly.

4. The combination with a well having tubing therein, of a tubing catcher mounted on the tubing and including a slip assembly, a wedge block and retarding means, said wedge block adapted to expand the slips of said assembly into gripping engagement with the wall of the well, and said retarding means comprising a ring normally lying out of contact with the wall of the well and functioning upon too rapid descent of the slip assembly to increase its sustaining area in a horizontal direction under fluid pressure within the well, and to contact with

the wall of the well to exert frictional resistance to the descent of the slip assembly.

5. A combination as claimed in claim 4, in which the ring is of inverted cup formation and pivotally mounted on the slip assembly.

6. A combination as claimed in claim 4, in which the ring is of inverted cup formation and radially split to provide a plurality of pivotally connected sections.

7. A combination as claimed in claim 4, in which the ring is pivotally connected to the slip assembly, said pivotal connection permitting the ring to reciprocate from side to side.

8. The combination with a well casing having tubing therein, of a tubing catcher mounted on the tubing and comprising a wedge block, a slip assembly, and fluid pressure actuated retarding means for the slip assembly, said means normally lying out of contact with the wall of the well and adapted, upon too rapid descent of the slip assembly, to exert friction on the wall of the casing and retard the descent of the slip assembly, and means to permit the operator to set the catcher at any desired elevation in the well.

9. The combination with a well and tubing arranged therein, of a tubing catcher mounted on the tubing and comprising a slip assembly, a wedge block and fluid pressure operated retarding means for the slip assembly, said retarding means normally lying out of contact with the wall of the well and being adapted, upon too rapid descent of the slip assembly, to substantially prevent fluid in the well from passing between the retarding means and the wall of the well, and also frictionally engaging the wall

of the well to retard the descent of the slip assembly, said wedge block being adapted to expand the slips of the slip assembly into gripping engagement with the wall of the well.

45

10. The combination with a well having a tubing arranged therein, of a tubing catcher mounted on the tubing and including a wedge block, a pin projecting from the tubing, a sleeve slidably mounted on the tubing and normally resting on the pin, gripping slips connected to the sleeve, engaging the wedge block and adapted to be moved by the latter into engagement with the wall of the well, a retarding ring pivotally mounted on said sleeve and normally lying in spaced position relatively to the wall of the casing, said retarding ring functioning upon too rapid descent of said sleeve to increase its sustaining area in a horizontal direction under fluid pressure within the well, and to contact with the wall of the well to exert frictional resistance to the descent of the slip assembly, a second sleeve slidably mounted upon the tubing and having downwardly extending slot merging into a substantially horizontal notch, said pin projecting into the notch and normally preventing the second sleeve from moving upwardly on the tubing, and adapted when the tubing is turned, to enter said slot, and springs connected to the second sleeve and engaging the wall of the well for preventing said sleeve from turning; the first sleeve, when the pin moves downwardly in said slot, resting on the second sleeve and preventing the slips from descending while the wedge block expands said slips.
